UNITED STATES PATENT OFFICE.

WILLIAM A. RAYMENT, OF TAUNTON, MASSACHUSETTS, ASSIGNOR TO THE REED & BARTON CORPORATION, OF SAME PLACE.

DESIGN FOR A LAMP-BODY.

SPECIFICATION forming part of Design No. 28,735, dated May 31, 1898.

Application filed March 7, 1898. Serial No. 673,012. Term of patent 14 years.

To all whom it may concern:

Be it known that I, WILLIAM A. RAYMENT, a subject of the Queen of Great Britain, residing at Taunton, in the county of Bristol and 5 State of Massachusetts, have invented and produced a new and original Design for Lamp-Bodies, of which the following is a specification, reference being had to the accompanying drawings, forming part thereof.

Figure 1 is a perspective view of a lamp-body showing my new design. Fig. 2 is a side elevation thereof.

The leading or material feature consists of the design forming the subject of the accompanying illustration. In such illustration the 15 globular bowl C is lined to simulate the ap-

pearance of a golf-ball and is shown as supported by a series of golf-clubs A, whose heads rest upon a base B and whose shafts are crossed beneath the bowl. On the base 20 B is produced in relief the representation of a flag at B' and balls at B², and is produced at B³ a depression simulating a golf-hole.

Having thus described my invention, what I claim as new, and desire to secure by Letters 25 Patent, is—

The design for a lamp-body as herein shown and described.

WILLIAM A. RAYMENT.
